UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

COUPLER-POSITIONING DEVICE.

Application filed April 19, 1926. Serial No. 102,977.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range".

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the number of broken knuckles and guard arms on couplers which members are frequently

bent or broken when the couplers are not within coupling range. Such devices also reduce the number of accidents to trainmen as they are not required to go between the cars and position the coupler preparatory to coupling.

It has been found advantageous to have the coupler support cast integral with the striking casting to obtain a four sided member which reinforces the end sill, draft sill, and associated parts and my device is especially adaptable to such a combined casting.

One or more eccentric rollers or eccentric rockers are frequently placed between the coupler and its support or between the coupler carriage and its support, as the case may be, which devices raise the coupler as they roll or rock to one side, thus causing the coupler to return to central normal position by gravity. Such devices also cause the coupler to move laterally when the car is on a curved track. When a single roller or rocker is used it does not stabilize the coupler, that is, prevent it from revolving around its own longitudinal axis. An object of the invention is to provide means independent of the positioning device which prevents the coupler from tipping abnormally.

In the drawings:

Fig. 1 shows a typical application of the device to a railway car.

Fig. 2 is a section on line 2-2 of Fig. 1.

Figs. 3 and 4 are diagrams showing a preferred form in normal position and extreme lateral position, respectively.

The striking casting or buffer block 2 is attached to the draft sill 3 or other part of the car body in any suitable manner and the coupler support 4 is attached thereto, or preferably cast integral therewith. The coupler 5 rests upon the carriage 6 which engages the support in such a manner as to restrict its movement longitudinally of the car but permits its movement sidewise of the car. This is preferably accomplished by providing a U-shaped support having spaced apart walls 7-8 between which the carriage moves in one direction but is restricted in its movement longitudinally of the car. The carriage is provided with means 10 to restrict lateral movement of the coupler relative thereto.

In the construction illustrated an eccen-

- tric roller 12 is interposed between the carriage and the support so that as it rolls to one side it raises the coupler. The coupler support has its upper surface 40 substantially coincident with the path described by the coupler in its lateral movement, or as preferred, the upper surface of the support may be spaced apart from and substantially parallel to the path described by the coupler 10 in its lateral movement. With this arrangement the coupler can only tip an immaterial amount before it engages the upper surfaces of the support.

While I have illustrated a single roller 15 type of coupler positioning device, it is understood that my invention may be used with any of the various types of positioning devices upon the market, such as the roller type; rocker type; single or double roller or 20 rocker type or the type having a swingingly suspended carrier. The contour of the upper surface of the rigid support depends upon the type of positioning device used.

I claim:

- 25 1. In a railway car; the combination of a laterally movable coupler, a single eccentric roller which raises the coupler upon lateral movement thereof, and a member positioned below the coupler with its upper surface 30 substantially parallel to the path described by the coupler upon lateral movement.

2. In a railway car; the combination of a laterally movable coupler, a coupler carriage with means to restrict the lateral movement 35 of the coupler relative thereto, a U-shaped coupler support with its upper surfaces substantially parallel to the path described by the coupler in its lateral movement whereby the coupler is prevented from tipping, and a single eccentric roller 40 interposed between the carriage and the support which raises the coupler upon lateral movement thereof, a portion of said carriage extending within the support so as to restrict 45 its movement longitudinally of the car.

3. In a railway car; the combination of a laterally movable coupler, a coupler carriage with means to restrict the lateral movement 50 of the coupler relative thereto, a U-shaped coupler support with its upper surfaces substantially parallel to the path described by the coupler in its lateral movement whereby

the coupler is prevented from tipping, a single eccentric roller interposed between the carriage and the support which raises the coupler upon lateral movement thereof, a portion of said carriage extending within the support so as to restrict its movement longitudinally of the car, and another portion extending over the support so as to restrict its downward movement.

4. In a railway car; the combination of a laterally movable coupler, a coupler carriage with means to restrict the lateral movement of the coupler relative thereto, a coupler support with its upper surfaces substantially parallel to the path described by the coupler in its lateral movement whereby the coupler is prevented from tipping, and a single eccentric roller interposed between the carriage and the support which raises the coupler upon lateral movement thereof, said carriage interacting with the support to permit the longitudinal but to restrict the lateral movement of the carriage.

5. In a railway car; the combination of a laterally movable coupler, a coupler carriage with means to restrict the lateral movement of the coupler relative thereto, a coupler support with its upper surfaces substantially parallel to the path described by the coupler in its lateral movement whereby the coupler is prevented from tipping, and a single eccentric roller interposed between the carriage and the support which raises the coupler upon lateral movement thereof, said carriage interacting with the support to permit the longitudinal but to restrict the lateral movement of the carriage and also to restrict its downward movement.

6. In a railway car, the combination of a laterally movable coupler, a coupler carriage with means to restrict the lateral movement of the coupler relative thereto, a coupler support, and a single roller interposed between the support and the coupler carriage co-acting with a portion of the support to raise the coupler upon lateral movement thereof, said support having another portion adjacent the coupler having an upper surface substantially parallel to the path described by the coupler upon lateral movement.

VINTON E. SISSON.
